UNITED STATES PATENT OFFICE.

LODOVICO BECCARI, OF BOLOGNA, ITALY.

VIAL FOR THE CONSERVATION OF MEDICAMENTAL LIQUIDS.

1,382,163.

Specification of Letters Patent. Patented June 21, 1921.

Application filed July 18, 1919. Serial No. 311,876.

To all whom it may concern:

Be it known that I, Lodovico BECCARI, a subject of the King of Italy, and residing at Bologna, Italy, (whose post-office address is 5 Via Saragozza 22, Bologna, Italy,) have invented certain new and useful Improvements in Vials for the Conservation of Medicamental Liquids, of which the following is a specification.

10 This invention relates to improvements in the construction of glass vials for the conservation of medicaments to be used for hypodermic purposes.

15 It is well known that the hypodermic medication requires, as its essential condition, the most perfect sterility of the medicamental solutions.

20 This is obtained in part with the usual glass vials now extensively employed, but such vials present numerous drawbacks due to the manner in which the same are broken to provide an outlet therein. The breaking of the neck of the device is not so easy as it may appear, and practice is required before a clean break can be assured, 25 which is essential, especially to avoid finger wounds.

30 Furthermore, during the breaking operation, there is the possibility for the fingers to come into contact with the liquid, thus destroying its perfect sterility and consequently the chief purpose of the vial.

35 The object of the present invention is in the elimination of the disadvantages stated above. This is attained by establishing in the vial neck a point of less resistance, in which the breaking shall necessarily take place; also that the breaking of the glass neck may occur easily without the risk of 40 shattering the entire vial.

45 Obviously, by the construction of a glass vial possessing a predetermined breaking point in the neck there will be no danger of one's hands coming in contact with the break.

50 A vial in accordance with the present invention, and embodying the advantages stated, is illustrated by the accompanying drawings in which:

55 Figure 1 is an enlarged view in section of the neck and upper portion of a glass vial.

Fig. 2 is a view showing the manner in which the vial is held prior to breaking the neck portion from the body. Fig. 3 is a 60 similar view to that of Fig. 2 showing the

neck portion having been broken away from the main body of the vial.

The vial, of course, may be of any form and size, formed from a body of thin glass, and having a reduced portion or neck which 60 may be easily broken at a determined point, which may be the most suitable for the drawing out of the contents of the vial by means of a syringe, thus preventing the danger of the vial breaking into one's hands. 65

Furthermore the breaking point is located at a considerable distance from where the vial is held which eliminates the danger of the fingers coming into contact with the liquid contents. 70

Referring to Fig. 1 of the drawing the main body A of the vial is provided with a reduced neck portion B extending above the main body and bent substantially at right angles to the axis of the body. A globular 75 swelling C is blown in the neck at a point beyond the elbow. The extended portion of the neck beyond the swelling C is closed by pointed portion D which serves to seal the vial. The enlarged portion of the neck retains any of the contents of the vial that may be in the neck when it is broken. This enlarged portion also serves to insure the 80 breaking of the bottle neck at a definite place when the bottle is to be opened. 85

Originally the neck B, when making the vial is straight, but it is then bent to about 90° by heating it. Now as the glass thickness is uniform, when the tube or neck B is bent, to the vertex of the angle formed, 90 there occurs a variation of the thickness, viz: the wall E forming the inner side of the elbow becomes thicker, while the outside wall F becomes thinner. The outer wall of the elbow, because of the drawing 95 of the glass to stretch over a greater area following the heating and bending operation, originates a weak spot or a point of little resistance. If the bent portion of the neck is forced toward its straight or original 100 position when cold, a breaking will take place at the vertex of the angle formed by the bending.

From the above description it is evident that for opening the vial the body A may 105 be held with one hand, and with the other hand holding the portion D, and then forcing this portion upward, as indicated by the arrow, thus producing a breaking at the bending. 110

Having now particularly described and ascertained the nature of my said invention and in what manner the same is to be performed, I declare that what I claim is:

- 5 1. A glass vial comprising a container having a body and an extended neck, an enlarged globular portion on the neck, the neck being bent between the body and the globular portion so that the neck extends at right angles to the body, the outer wall of the bent part being thin whereby the neck may be easily broken.
- 10 2. A glass vial comprising a container

having a body and a sealed neck, said neck being bent in the form of an elbow and having one wall of the elbow thinner than the other part thereof, whereby the neck can be easily broken. 15

In testimony whereof I have hereunto signed my name in the presence of two witnesses. 20

LODOVICO BECCARI.
